[57] CLAIM

The ornamental design for donut icing device, as shown
and described.

DESCRIPTION

FIG. 1 is a partially exploded perspective view of a
donut icing device showing my new design;

FIG. 2 is a top plan view thereof with the press panel
removed;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

FIG. 8 is a top plan view of the press panel of the donut
icing device;

FIG. 9 is a bottom plan view thereof;

FIG. 10 is a left side elevational view thereof;

FIG. 11 is a right side elevational view thereof;

FIG. 12 is a front elevational view thereof; and,

FIG. 13 is a rear elevational view thereof.
